DECORATIVE SEAT BRACE

Roland A. Faulhaber, Memphis, Tenn., assignor to
Troxel Manufacturing Company, Moscow, Tenn.

Term of patent 14 years

Filed Apr. 2, 1968, Ser. No. 11,267

Int. Cl. D12—14

U.S. Cl. D90—15

FIG. 2

FIG. 1

FIG. 3

FIG. 1 is a perspective view of a decorative seat brace showing my new design.

FIG. 2 is a fragmentary front elevational view of the ornamental seat brace of FIG. 1.

FIG. 3 is a side elevational view thereof as viewed from one side. The side elevational view from the opposite side from that shown in FIG. 3 is a mirror image thereof.

The bicycle shown in broken lines in FIGURE 1 is included for illustrative purposes only.

I claim:

The ornamental design for a decorative seat brace, as shown and described.
